SAFETY RAZOR

Filed Feb. 16, 1927

FIG. 1

FIG. 3

FIG. 2

FIG. 4

FIG. 5

INVENTOR
Ramón Aguilar
BY *Julian Opolasky*
ATTORNEY

UNITED STATES PATENT OFFICE.

RAMÓN AGUILAR, OF NEW YORK, N. Y.

SAFETY RAZOR.

Application filed February 16, 1927. Serial No. 168,604.

This invention relates to safety razors and particularly to a novel guard for safety razors. The invention has for an object the provision of an adjustable guard adapted to be suitably positioned for protecting the surface being shaved.

Another object of the invention is the provision of a safety razor guard having an extensible side member adapted to be adjustably positioned for varying the closeness of cut of the blade.

For further comprehension of the invention and of the objects and advantages thereof, reference will be had to the following description and accompanying drawings and to the appended claims in which the various novel features of the invention are more particularly set forth.

Referring to the drawings:

20 Fig. 1 is a side elevational view of a razor embodying my invention.

Fig. 2 is a top plan view of the razor shown in Fig. 1.

Fig. 3 is an elevational view, partly in section, of a razor embodying my invention.

Fig. 4 is a sectional view taken on the line 4—4 of Fig. 2.

Fig. 5 is a fragmentary view of a safety razor guard embodying my invention.

30 Referring particularly to the drawings, the numeral 10 designates a handle member, 11 a top shield and 12 the screw threaded stud secured to said top shield and employed in clamping the blade 13 between the top shield 11 and my improved bottom guard 14, the shield, stud, handle, and blade being of well known construction.

The guard 14 comprises a metal plate having a curvature conforming with the curvature of the lower surface of the top shield 11 and is provided with an opening 15 to receive the stud 12. The longitudinal edges of the metal plate 13 are serrated, being provided with rectangular teeth 16 as shown in Fig. 4. Recesses 17, terminating at a shoulder 18 are provided along the lower longitudinal edge portions of the guard 14 and are extended into the guard beyond the base of the teeth 16. Spaced apart dove-tailed, transverse slots 18' communicating with the recesses 17 are provided on the lower surface of the guard member 14 as shown in Fig. 4.

55 Supplementary adjustable edge members 19 are mounted on the guard 14 in the longitudinal recesses 17 therein. The supplemen-

tary edge 19 comprises a longitudinal bar 20 provided with spaced projections 21 extending rearwardly therefrom having beveled edges adapted to conform with the shape of the dove-tailed recesses. A plurality of forwardly disposed extensions 22 having supplementary teeth sections 23 at the outer extremity thereof are made integral with the bar 20. The supplementary teeth sections 23 project upwardly from the extensions 22 and are provided with a shoulder 24 adapted to engage the end of the rectangular teeth 16 when the supplementary edge member is in its retracted position. The supplementary teeth sections 23 are rounded at their outer extremity, as at 25, providing a smooth surface for engaging the face. It should be understood that there are as many supplementary teeth sections 23 as there are rectangular teeth 16. Resilient spring extensions 26 extending rearwardly from each of the extensions 21 are attached at one end to said extensions by the pins 27 and are disposed downwardly and engaged in the notches 28 of the lower surface of the guard 14 as shown in Fig. 3.

In operation the supplementary guard edge 19 may be extended or retracted as desired to adapt the razor for making a rough or smooth shave respectively. When the supplementary guard is retracted the edge 29 of the blade 13 extends outwardly relative to the rounded end 25 of the teeth sections 23 and the cutting edge is permitted to closely engage the surface being shaved but when the supplementary guard is extended, the teeth 23, engaging the surface being shaved, prevent the blade to approach said surface. It should be understood that individual adjustment of each supplementary guard may be effected by lifting the spring 26 by means of the knobs 30 mounted thereon, and positioning the ends of the springs in the desired notches. If desired one edge guard may be set for producing a rough shave and the other edge for effecting a smooth shave and these edges may be used alternately.

Having thus fully described and shown an embodiment of my invention, what is desired to be secured by Letters Patent of the United States is:

1. In a safety razor comprising a bottom guard member having longitudinal recesses along the edges thereof, rectangular teeth on the edges of said guard, bars slidably mounted in said recesses, supplementary

teeth sections on said bars adapted to be positioned in close proximity to said rectangular teeth for extending the length thereof and a blade disposed above said bottom 5 guard comprising cutting edges, said supplementary teeth sections being adapted to be extended to various positions in advance of said cutting edges.

2. In a safety razor comprising a bottom 10 guard member having longitudinal recesses along the edges thereof, rectangular teeth on the edges of said guard, bars slidably mounted in said recesses, supplementary teeth sections on said bars adapted to be 15 positioned in close proximity to said rectangular teeth for extending the length thereof, a blade disposed above said bottom guard comprising cutting edges, said supplementary teeth sections being adapted to be extended to various positions in advance of 20

said cutting edges and means for retaining said supplementary teeth in an adjusted position comprising a spring clip engageable with spaced notches in the lower surface of said guard. 25

3. A safety razor comprising a bottom guard, having spaced notches on the lower surface thereof and spaced transverse recesses therein, an adjustable edge member on said guard comprising spaced extensions 30 slidable in said recesses and locking means comprising spring members mounted on said adjustable edge members at one end and adapted to engage said notches at their other ends for retaining said edge members in an 35 adjusted position.

In testimony whereof I have affixed my signature.

RAMÓN AGUILAR.
